UNITED STATES PATENT OFFICE

ALBERT G. FISCHER, OF CHICAGO, ILLINOIS, ASSIGNOR TO THE PHILIP CAREY MANUFACTURING COMPANY, A CORPORATION OF OHIO

CONTAINER FORM FOR EXPANSION JOINTS

Original application filed June 19, 1922, Serial No. 569,247. Divided and this application filed November 19, 1925. Serial No. 70,077.

This is a division of my application Serial No. 569,247—Container form for expansion joint and method of installing same, filed June 19, 1922, and particularly refers to the envelope as such constructed from non-metallic fabricated sheet material, having a suitable coating which readily binds with the concrete surface upon the application of heat.

Figure 1 is a perspective view of a portion 10 of the folded non-metallic sheet material from which I construct one form of the container.

Figure 2 is a similar view showing the extended crowning edges.

Figure 3 is a similar view showing a modified form of the base portion, the same being collapsed.

Figure 4 is a similar view showing the base portion folded longitudinally but not completely collapsed.

Figure 5 is a similar view showing still another form of base portion.

It may be readily understood that a low melting point material would readily unite 25 with the concrete in the temperature of the sun upon the concrete surface in summer weather, or by the use of a high melting point material would be dependent upon the filler and the heat imparted from the inside of the envelope from the filler for adhesion to the concrete face.

It has been the early practice in providing expansion joints to place a strip of wood at the intersection in the roadway, where it is 35 desired to provide for the expansion and contraction of the concrete, and later remove the strip and pour heated bituminous matter in the crevice.

This method was superseded by pre-moulded joints installed at the time of pouring the concrete. However, it has since been found that joints with felt sides and others having interfering substances on the sides do 40 not adhere to the walls of the concrete and consequently do not keep the crevice water-proof.

It is also customary to allow the joint to protrude one half to one inch above the 50 finished surface, so that the traffic will work

this edge over the edges of the concrete on either side of the joint.

When pouring the joint heretofore a V has been formed by the heated material in settling, and this necessitates going over the 55 crevice several times with heated material, until filled. But then no surplus was provided, as in the case where half to one inch was allowed to project, when a premoulded joint is used.

My improvement performs two important functions, it provides a means to compel adhesion to the side walls of the concrete, and also it provides a means for forming a protruding edge to take the wear of the traffic 65 and protect the edges of the concrete. It also prevents tearing away concrete when pulling the spacing board, which frequently happens in removing the wooden strips.

I furnish a container form in the shape 70 of a covering which will fit the spacing board and protrude above the surface of the concrete. This envelope is made of saturated felt preferably, but may be made of any suitable non-metallic fabricated sheet material, such as, paper, cloth, burlap, canvas, or other substances. The outside is preferably coated 75 with a fair coating of bituminous or other suitable adhesive.

The envelope is placed about the spacing or backing board and staked in position. The concrete is poured and allowed to set. The envelope has a flanged base over which the concrete is placed and which sets as a holding means in preventing the container form raising upon pulling out the backing or spacing board. When the board is removed the container remains in place and is filled with suitable filler. These fillers are usually heated 85 to 300 or 400 degrees, and this temperature 90 will naturally compel adhesion by melting the material on the outside of the container or the material with which the container is saturated.

Steel container forms are objectionable for 95 the reason that they must provide anchoring means in the concrete to hold them in place, because the concrete will not adhere to the metal sides, with the result that rust soon sets in and the rusted parts act as an inter-

ferring means between the asphalt and the slabs. Likewise metal is not shock proof, as is a piece of felt, and the result is that the continuous shock of the traffic imparts impact to the metal and breaks the asphalt mass contained therein into particles in the winter cold, so that when the early spring rains occur the asphalt is washed out in lumps and a defective joint is made.

10 This does not occur where the felt sides are used, which take up the shock and protect the mass enclosed therein. Likewise the mastic on the sides of the felt cause adhesion to the cement surfaces, whereas the 15 metal container does not have this advantage. This container may also be filled away from the work and inserted as a preformed joint, having adhesive material on its sides, in which case the adhesive material would be of 20 a lower melting point.

Referring now to the drawing in detail C represents the non-metallic fabricated sheet folded to provide the spaced side walls with a base portion yoking the same together and 25 cooperating therewith to develop a container form. As shown in Figure 2 the crowning edges of the side walls are adapted to be folded inwardly to project above the surface of the concrete in which the form is installed, 30 so as to enable the poured filler to also project and be mushroomed down by traffic, so as to cover the edges of the concrete slabs between which the joint is installed. The folds in the crowning edge have no particular significance since the same result is accomplished by making the side walls tall enough 35 so as to accomplish this purpose.

To utilize the device in an ordinary spacing strip as previously referred to, it is inserted in the form and the form together with the spacing strip is then set up in position so that the concrete is poured around the assembly, and after the concrete has set to a predetermined extent the spacing strip is 45 removed and the filler poured into the container form.

As shown in Figure 3 the base portion may be made with projecting flanges *d-d* disposed transversely of the side walls so as 50 to interlock the concrete slabs between which the joints are installed, in fact they would be imbedded under the concrete. Such a structure would prevent the joint filler and envelope from raising out of the joint.

55 It so happens that in Figure 3 the projecting flanges are shown collapsed, so as not to take too much room in shipping. The flanges may be collapsed by providing longitudinal flanges on the base portion nearest 60 the side walls C, so that the flanges may assume substantial alignment with the vertical plane of the side walls.

The same form of the invention is illustrated in Figure 4, only the base portion is not 65 as completely collapsed as in Figure 3.

In Figure 5 the base portion is made with squared flanged projections *d-d*. In this form the collapsible feature of the base portion can be accomplished as well as with the form shown in Figures 3 and 4, and at the same time it develops an exceptional structure.

It may readily be understood that many modifications may be made in this invention. The joint may be installed in reservoirs, walls, 75 sidewalks and buildings, or used for other construction purposes.

The filler may either be solid or compressible or cellular, as desired. Likewise the spacing strip need not be necessarily have a cap strip, and the spacing strip may be made of any suitable material that will yield to the traffic in reducing the protruding part of the joint.

The container or envelope fitting over the 85 spacing strip and later becoming the mould in the concrete, need not necessarily be restricted to straight protruding edges, but the edges may be slightly curved in, as shown in Figure 3, now Figure 2, and may be held in 90 place by the cap strip —*b*— old Figure 1. The container may be used for any filling material adapted for expansion or marking purposes.

I claim:

1. A container form for poured expansion joints, comprising a non-metallic fabricated sheet of sufficient thickness and rigidity substantially to hold its shape and folded upon itself to provide side walls, and a base portion yoking together said side walls and cooperating therewith to provide a container form, said container having its sides coated with a low melting point material readily unitable with concrete.

2. A container form for poured expansion joints, comprising a non-metallic fabricated sheet folded upon itself to provide side walls, and a base portion yoking together said side walls, and a longitudinal fold in the base portion intermediate the side walls, permitting the base portion to collapse with the projecting flanges thereof and to move into a plane substantially in alignment with the side walls, said sheet being of considerable thickness whereby said container will remain in open erect position to receive poured filler and said sheet carrying a coating with a low melting point material which will readily unite with concrete in the temperature of the sun upon 105 the concrete surface in the summer weather.

3. A non-metallic container having walls of considerable thickness and rigidity adapted to have a bituminous filler poured thereto 110 whereby said container and filler will act as expandable and contractible constructional material, said filler having its sides coated with a low melting point material which will readily unite with concrete in the tempera- 120 130

ture of the sun upon the concrete surface in the summer weather.

4. Constructional material comprising a water-proofed fibrous envelope adapted to receive water proofed filling material, said envelope having integral sides and a bottom and being open at the top, said envelope carrying a coating of low melting point material adapted readily to unite with concrete in the temperature of the sun upon the concrete surface in the summer weather and said envelope being of sufficient thickness and rigidity to maintain itself in open form when open for filling.
5. A container adapted to receive water proofed filler whereby to form expandable and contractible constructional material, said container comprising an envelope of non-metallic sheet material saturated with water proofing material and carrying an exterior coating of a low melting point adhesive material that will readily unite with concrete in the temperature of the sun upon the concrete surface in the summer weather.
- 25 Signed at Chicago, Ill., this 17 day of November, 1925.

ALBERT C. FISCHER.
